(57) **CLAIM**

The ornamental design for a digital video recorder for monitoring, as shown and described.

DESCRIPTION

FIG. 1 is a front, top and right side perspective view of a digital video recorder for monitoring, showing my new design;

FIG. 2 is a perspective view thereof with a tray in a drawn out state;

FIG. 3 is a top plan view thereof;

FIG. 4 is a front elevational view thereof;

FIG. 5 is a rear elevational view thereof;

FIG. 6 is a right side elevational view thereof; the opposite side being a mirror image thereof; and,

FIG. 7 is a bottom plan view thereof.
